(57) CLAIM

The ornamental design for a holder for headphone, as shown and described.

DESCRIPTION

FIG. 1 is a perspective view of a holder for headphone showing our new design;

FIG. 2 is a front elevational view thereof, showing a line VIII—VIII;

FIG. 3 is a rear elevational view thereof;

FIG. 4 is a left side elevational view thereof;

FIG. 5 is a right side elevational view thereof;

FIG. 6 is a top view thereof, a bottom plan view thereof being a mirror image;

FIG. 7 is a reduced perspective view thereof, showing a using condition; and,

FIG. 8 is a reference cross sectional view thereof; taken along the line VIII-VIII shown in FIG. 2.

The broken lines showing of the environment are for illustrative purposes only and form no part of the claimed design.
